United States Patent

Des. 240,497
Patented July 13, 1976

240,497

CAN OPENER PUNCH

Ferris E. Riba, 3722 E. Milton,
Tucson, Ariz. 85706

Filed Sept. 18, 1974, Ser. No. 507,233

Term of patent 14 years

Int. Cl. D7—99

U.S. Cl. D8—18

fig. 1

fig. 2

fig. 3

FIG. 1 is a perspective view of a can opener punch showing my new design;

FIG. 2 is a side elevational view thereof, the side opposite being a mirror image; and

FIG. 3 is a bottom plan view thereof.

I claim:

The ornamental design for a can opener punch, as shown and described.
